TUMBLING MILL

George M. Howard, Cincinnati, Ohio

Application July 21, 1944, Serial No. 545,892

4 Claims. (Cl. 51—164)

1

This invention relates to a tumbling mill of the type used for finishing the surfaces of metal articles and parts to remove spurs, and similar surface roughness and projections that result, for example, after casting or molding of such articles. This finishing is accomplished by the use of suitable abrading elements commonly known as stars, but which are frequently of spherical form, such as ball bearings.

An object of the invention is to provide a tumbling mill of this character in which the articles to be finished or polished are placed in the tumbling drum through a side opening therein and similarly removed therefrom, while the abrading elements require no handling whatever, being injected into or emptied from the tumbling drum by rotation of the latter in one direction or the other.

Another object of the invention is the provision of an end compartment associated with the tumbling drum into and from which the abrading elements may be passed through a conduit exteriorly of the tumbling drum and communicating with the side of the drum and with said compartment.

Another object is the provision of novel means for mechanical handling of the abrading elements whereby the tumbling drum may be emptied of or replenished with the elements in a few revolutions of the drum.

Another object is the provision in a mill of the kind described, of novel means for passing air currents through the drum and the associated compartment means whereby dust and particles are carried off during all movements of the abrading elements and operated in the tumbling mill.

Another object is to provide cross-currents of air passing through the tumbling mill for effectively contacting all parts of and materials in the mill.

Another object is the provision of a mill incorporating the features mentioned and constructed in a simple and efficient manner.

These and other objects are attained by the means described herein and illustrated in the accompanying drawings in which:

Fig. 1 is a side elevational view of a tumbling mill of this invention with the tumbling drum deer in open position, and with parts of the mill broken away for the sake of disclosure.

Figs. 2, 3, 4 and 5 are cross-sectional views on the lines 2, 3, 4 and 5 respectively of Fig. 1.

Fig. 6 is a detailed cross-sectional view showing the connection between the "tramp iron trap"

2

and the associated sleeve-forming parts of the tumbling mill.

One of the chief disadvantages of tumbling mills as now known is the length of time required to empty and replenish the mill, not only as to the articles operated upon but likewise as to the abrading elements utilized. The present invention greatly expedites these operations by providing a side opening tumbling drum into which the articles operated upon may be inserted and removed instantly and by providing, in addition, lateral openings in the tumbling drum and means associated therewith for excluding the operated articles but receiving the abrading elements and passing the latter exteriorly of the drum, upon rotation of the latter in one direction into a compartment, the same conduit means being operative upon reverse rotation of the drum, for returning the abrading elements to the latter, these emptying and replenishing operations being accomplished within a few rotational movements of the drum.

Another difficulty heretofore in devices of the kind here under consideration, has been the carrying off of dust and minute particles, an operation essential for the provision of a proper working environment. The passage of an air current through a tumbling mill has been previously utilized but the effect has been only partially satisfactory since the current of air cuts a more or less direct path through the drum and contacts only a portion of the parts and materials in the mill. The present invention eliminates this disadvantage by providing means to create irregular, divergent and cross-currents of air through the mill so that the dust and particles are effectively carried off.

Other advantages of the invention will become apparent upon consideration of the details of disclosure that follow.

With reference to the several figures, the tumbling mill of this invention is mounted for horizontal rotation and comprises a tumbling drum 12 which may be generally octagonal in cross-section as shown in Fig. 2 which shape has been found to produce an effective tumbling action. One of the surfaces thus provided may be substantially cut away as at 13 to provide an opening through which operated articles are inserted into and removed from the drum, this opening being suitably closed by a door 14 conforming in shape to the contour of the associated drum part, the door being suitably held in its closed position by convenient closure means 55 as indicated at 15.

At opposite sides of the drum, the contour of the latter is interrupted to provide a pair of longitudinally-extending openings 16 and 17, Figs. 2 and 3, which are employed for removing from and restoring to the drum, the abrading elements utilized therein. Each opening 16 and 17 has associated therewith a pair of shallow walls 18 and 19 projecting angularly of the surface of the drum and extending divergently from the center of the respective openings 16 and 17, to the ends of the drum, and forming guides for the abrading elements entering or leaving the openings 16 and 17, as will be further described. As seen in Fig. 2, the inner end edges of these shallow walls 18 and 19 connect with the respective edge portions of the interrupted drum sections which form the openings 16 and 17. At each end of the drum 12, a compartment 20 and 21 is secured, the compartments being thus rotatable with the drum, and the inner end walls of the compartments closing the ends of the drum, as indicated at 22 and 23, Fig. 1. The two compartments, as seen in Figs. 2 and 3, are of somewhat larger cross-sectional outline than that of the drum 12 and they are preferably of circular form. The said inner end walls 22 and 23 of the two compartments are each provided, at a point exteriorly of the drum 12, and substantially midway between the openings 16 and 17, with a pair of ports 24 and 25, one of the ports being provided at each outer end of the respective guide walls 18 and 19.

The mill is mounted for horizontal rotation between standards 26 and 27, Fig. 1, through the medium of shafts 28 and 29 which extend respectively through the compartments 20 and 21 and which have their inner ends secured as at 30 to the inner end walls 22 and 23 of said compartments. The outer ends of shafts 28 and 29 are suitably retained in roller mountings as at 31 and 32.

At one end of the mill, as on the standard 27, Fig. 1, drive means, such as the reversible motor 33 are provided, movement therefrom being transmitted to the mill by a chain and sprocket unit 34, or other suitable connection, operating on the shaft 29.

Each of the compartments 20 and 21 is provided interiorly with a spiral guide or rib 35 and 36, the ends of which are secured adjacent and diverge away from the respective ports 24 and 25 as indicated at 37, Fig. 1, so as to carry abrading elements away from or toward the said ports, depending upon the direction of rotation of the mill, as will be further described.

The present invention involves the use of air currents passed through the tumbling mill for removing dust and particles therefrom. For this purpose a suitable source of air under pressure is provided exteriorly of the mill and is transmitted thereto through a suitable duct 38, Fig. 1, this duct likewise serving to carry off the removed dust particles. It is contemplated herein that suction be applied to the mill through this duct. That is to say, air is drawn into the mill at the end opposite the one where the suction is applied. In the present embodiment of the invention, the said opposite end is represented by the outer or end wall of the compartment 21, which as seen in Fig. 4, may be provided with openings 39 which, interiorly of the compartment, are covered by perforate plates 40. Air may thus be drawn through the compartment 21, into the drum through the adjacent diagonal conduits and the openings 16 and 17, thence outwardly of the drum

through the conduits and ports at the other end of the drum, after which the current of air is drawn outwardly through the compartment 20 and into the duct 38. Within the compartment 20, the shaft 28, is surrounded by a perforated sleeve 41 which extends outwardly beyond the outer end of said compartment, the extreme outer end 42 of the sleeve being sealed about the shaft 28.

10 The outer end portion of the sleeve 41 is shown as associated with a "tramp iron trap" 43 which is in effect merely a box member embracing the sleeve 41 and provided with openings through which the sleeve passes. The edges of these 15 openings, as indicated at 44, Fig. 6, are in sealed but slideable relation with the sleeve 41. As shown, the sleeve for this purpose may have a pair of slightly spaced annular angular strips 45 between which the edge portions 44 of the box 20 apertures are slidably retained.

The bottom of the trap 43 may have a hinged door 46, Fig. 1, associated therewith, this door being provided with suitable means for automatic opening thereof when a predetermined 25 amount of weight has been deposited on the interior face of the door. At the upper end of the trap 43, the latter is placed suitably in communication with the duct 38, as shown in Fig. 5.

In operation, the articles to be finished or 30 abraded, such as castings, are placed in the tumbling drum through the opening 13 and thereafter the door 14 is closed and secured. It is to be understood that the drum has already been provided with a charge of suitable abrading elements, such as ball bearings or stars. It should 35 be further explained that the present mill in accordance with common practice, is intended for operation upon articles or objects larger than the abrading elements utilized in the mill. The driving motor 33 is now started for turning the mill in the tumbling direction, as indicated by the arrow at the right-hand side of Fig. 1 and at the left-hand side of Fig. 2. After the tumbling 40 operation is completed, the driving motor is reversed for rotating the mill in the discharge direction indicated by the arrow at the left-hand side of Fig. 1 and at the right hand side of Fig. 2. At this time, the abrading elements, which are of such size as to be received in the lateral openings 16 and 17 in the drum, are caused to enter the said openings and are then directed by the shallow guide walls 18 and 19 to the ports 24 and 25 at each end of the drum, the abrading elements 45 being thus carried exteriorly of the drum into the end compartments 20 and 21. Here the spiral guides 35 and 36 further direct movement of the abrading elements to the interior of the associated compartments. The door 14 on the side of the tumbling drum may now be opened 50 for the removal of the finished castings or other articles and another batch of unfinished articles may be placed in the drum, the door being again closed thereafter. The mill is now rotated in the opposite direction at which time the spiral guides 35 and 36 in the compartments 20 and 21, become 55 operative for directing the abrading elements outwardly through the associated ports 24 and 25 and through the diagonal guides associated 60 with the drum, to the interior of the latter, through the openings 16 and 17. The back and forth motion of the abrading elements as just described is unrestricted and as it takes place 65 simultaneously at both ends of the drum, the 70 emptying and replenishing operations are accom- 75 plished.

plished in a minimum of time, normally requiring only a few turns of the mill.

Simultaneously with the abrading operations just described, currents of air are passed through the mill, including the drum and the end compartments, in the manner already indicated. In as much as the currents of air induced into the right-hand end of the mill, Fig. 1, must traverse diagonal paths in entering the drum through the slanting star conduits, and must likewise follow similar diagonal paths in leaving the drum, the air is given a swirling motion and likewise a cross-current action, in as much as the ports 24 and 25 are oppositely disposed. In other words, the mass of air drawn in at one end of the drum, passes outwardly therefrom not only through the opposite end of the opening 17 through which the air may have entered, but likewise passes outwardly through the ports 24 and 25 at the opposite end of the drum. The result of such air action is that a thorough scouring of all the interior of the drum, the compartments, and their contents is effected.

With regard to the "tramp iron trap" it may be further explained that some relatively large particles of metal may be carried outwardly by the current of air. The drop in air pressure occurring within the trap 43 is sufficient to cause such particles to drop outwardly of the sleeve 41 onto the inner face of the door 46, which, after it has accumulated a predetermined weight of such particles, swings open to release the same and then automatically closes.

Variations will suggest themselves upon consideration of the means herein described by these, 35 are believed to be comprised within the spirit and scope of the invention.

What is claimed is:

1. A tumbling mill comprising a tumbling drum formed with a diagonal conduit leading into a 40 side of the drum and with an outlet, and means for inducing a current of air into the drum through said conduit and out of said outlet whereby a swirling air current is passed through 45 the drum.

2. A tumbling mill comprising a tumbling drum formed with oppositely-disposed conduits leading into and out of the drum, and means for inducing air through said conduits to produce swirling and cross-currents of air through the drum.

5 3. A tumbling mill comprising a tumbling drum formed with a diagonal conduit leading into a side of the drum and with an outlet, and means for inducing a current of fluid into the drum through said conduit and out of said outlet whereby a swirling fluid current is passed through the drum.

10 4. A tumbling mill comprising a drum for receiving articles to be abraded and abrading elements smaller than said articles, said drum having a peripheral outlet formed to permit passage of the abrading elements only, a compartment at each end of the drum, and each compartment having a port formed therein, divergent, abrading element guideways disposed exteriorly of the drum and extending between said outlet and the ports, an air opening formed in one compartment, a source of air under pressure, and means for connecting the air source with the other compartment whereby the divergent guideways create a swirling air current within the drum to carry off dust and dirt particles therefrom.

15 30 25 GEORGE M. HOWARD.
